UNITED STATES PATENT OFFICE.

WILEY H. PRIDGEN, OF CREEK, NORTH CAROLINA.

BALE-TIE.

1,190,456.

Specification of Letters Patent. Patented July 11, 1916.

Application filed October 9, 1914. Serial No. 885,870.

To all whom it may concern:

Be it known that I, WILEY H. PRIDGEN, a citizen of the United States, residing at Creek, in the county of Warren and State 5 of North Carolina, have invented a new and useful Bale-Tie, of which the following is a specification.

This invention relates to buckles for use in connection with bale ties, one of its objects being to provide a simple, durable and efficient buckle of this character which can be quickly assembled with the end portions of a tie and which, when reversed and clenched by any suitable means provided for 10 that purpose, will hold the ends of the tie secured together and at the same time draw said ends toward each other so as to cause the tie to bind tightly upon the bale or bundle surrounded thereby.

With the foregoing and other objects in view which will appear as the description proceeds, the invention resides in the combination and arrangement of parts and in the details of construction hereinafter described and claimed, it being understood 20 that changes in the precise embodiment of the invention herein disclosed, can be made within the scope of what is claimed, without departing from the spirit of the invention.

In the accompanying drawings, the preferred forms of the invention have been shown.

In said drawings:—Figure 1 is a plan view of the buckle and showing the positions of the end portions of a tie when assembled therewith during the first step in the operation of fastening the ends together. Fig. 2 is a view similar to Fig. 1 but showing the relative positions of the parts upon the completion of the second or tightening step. Fig. 3 is a plan view of the buckle and those portions of the tie in engagement therewith after the parts have been clenched together, thus completing the fastening operation. Fig. 4 is a section on line A—B Fig. 3. Fig. 5 is a perspective view of the buckle shown in Figs. 1 to 4 inclusive. Fig. 6 is a plan view of a modified form of buckle with the ends of the tie in position therein, and the buckle opened out prior to the clenching operation, the position of the end portions of the tie after the buckle has been reversed, being indicated by dotted lines. Fig. 7 is a section on line C—D Fig. 6 and showing the buckle clenched

upon the completion of the tying and tightening operation. Fig. 8 is a perspective view of another form of tie buckle in position upon the end portions of a tie. Fig. 9 60 is a section on line E—F Fig. 8. Fig. 10 is a perspective view of another form of tie buckle. Fig. 11 is a section on line G—H Fig. 10.

Referring to the figures, it will be noted 65 that the buckle shown in Figs. 1 to 5 inclusive is made of a single sheet of metal folded along longitudinal lines so as thus to produce parallel barrels 1 and 2 separated by a flattened loop 3, there being laterally 70 extending curved wings 4 and 5 extending from the barrels 1 and 2 as shown particularly in Fig. 5. In using this form of buckle, one end of a tie is inserted in one direction into the barrel 1 and is then bent 75 laterally at its terminal, this end portion of the tie being shown at 6 and its bent terminal being shown at 7. The other end portion 8 of the tie is then inserted in the opposite direction into the barrel 2 and its terminal bent or offset as shown at 9. With 80 the parts thus assembled, the barrels 1 and 2 are gripped within a suitable tool and the buckle is bodily reversed to the position shown in Fig. 2, thus causing the end portions 6 and 8 of the tie to be looped, the end portion 6 assuming a position above and longitudinally of the wing 5 while the end portion 8 assumes a position above but longitudinally of the wing 4. This operation 85 90 of reversing the buckle in the direction indicated by the arrows in Fig. 1 and to the position shown in Fig. 4, results in tightening the tie about the bale or other object surrounded thereby and as soon as the reversal of the buckle has been effected, the wings 4 and 5 are clenched onto the end portions 6 and 8 of the tie as shown in Figs. 3 and 4, thus holding the parts assembled securely so that there is no danger 95 100 105 of their becoming loose.

In Figs. 6 and 7 another form of buckle has been illustrated. This buckle instead of being formed with two barrels and an intermediate loop, is formed with a central up-standing loop 10 having oppositely extending wings 11 and 12. An aperture 13 is formed in one side of the loop 10 and another aperture 14 is formed in the other side of the loop and those portions of the loop 110 between the apertures and the adjacent ends of the loop are contracted so that non-align-

ing barrels 15 and 16 are thus produced. In using this form of the buckle the end portions of the tie are assembled in the same manner as heretofore described. One end portion 17 of the tie is inserted into the barrel 16 and bent at its terminal as shown at 18 while the other end portion 19 of the tie is inserted in the opposite direction through barrel 15 and its terminal is bent as shown 10 at 20. With the tie and buckle thus assembled, the buckle is reversed bodily in the direction indicated by the arrow in Fig. 6 so that the end portion 17 of the tie is thus brought to position above the wing 11, while 15 the end portion 19 of the tie is brought to position above the wing 12. The wings 11 and 12 are then clenched together as shown in Fig. 7, thus completing the tying operation. Obviously the tie will be tightened 20 in the same manner during this operation as during the operation described in connection with Figs. 1 to 5 inclusive.

Another form of buckle has been illustrated in Figs. 8 and 9. This buckle is likewise formed of sheet metal and is bent to produce a barrel 21, a loop 22 and a wing 23. In using this form of buckle, one end portion 24 of a tie is inserted through the barrel 21 and its terminal is bent back to 30 form a hook 25, after which said hook is drawn back into position over the wing 23. The other end portion 26 of the tie is then bent to form a hook 27, which hook is inserted into the loop 22 while the end portion 26 rests between the barrel 21 and the ring 23. After the parts have thus been assembled, the buckle is clenched as shown in Fig. 9. In this form of the device the buckle is not reversed as in the other forms 40 but merely constitutes a buckle and not a tightening means.

The form of buckle illustrated in Figs. 10 and 11 is made of a sheet of metal having incisions cut into the sides thereof at the 45 center, thus to form separate tongues. The tongues at one end are bent in opposite directions to form a barrel 28 and a wing 29, while the tongues at the other end are bent in opposite directions to form a barrel 30 and a wing 31. The end portion 32 of a tie is then inserted into the barrel 28 while the other end portion 32 of the tie is in-

serted in the opposite direction into the barrel 30. The buckle is then reversed so as to bring the end portions above the wings 29 55 and 31 whereupon the buckle is clenched as shown in Fig. 11 and the parts securely held together.

What is claimed is:—

1. A bale tie buckle consisting of a single 60 piece of sheet metal bent to form separate contacting parallel tie receiving barrels and a separate outstanding wing bendable along lines parallel with the barrels and toward said tie receiving portions, said wing constituting tie gripping means.

2. A bale tie buckle including a single piece of sheet metal forming parallel tie receiving barrels and clenching wings parallel with the barrels and bendable relative 70 thereto.

3. A bale tie buckle including a piece of sheet metal bent to form parallel barrels, for the reception of the end portions of a tie, and outstanding wings extending longitudinally of the barrels and constituting tie engaging portions.

4. The combination with a bale tie having parallel lapping terminal portions, each having an offset end, of a buckle having separate barrels engaging said parallel terminal portions, said tie having portions bent back along the outer sides of the barrels, and clenching wings outstanding from the barrels and bendable against said portions 85 outside of the barrels.

5. The combination with a bale tie buckle including a single piece of sheet metal forming parallel tie receiving barrels and outstanding clenching wings parallel with the 90 barrels and bendable relative thereto, of a tie having its end portions extended in opposite directions through the barrels and its terminals bent back along the outer faces of the respective barrels, said wings being 95 bendable about said terminals.

In testimony that I claim the foregoing as my own, I have hereto affixed my signature in the presence of two witnesses.

WILEY H. PRIDGEN.
